US00D841186S

(12) **United States Design Patent** (10) **Patent No.:** **US D841,186 S**
(45) **Date of Patent:** **** Feb. 19, 2019**

(54) **BIOCHIP**

(71) Applicant: **Tunghai University**, Taichung (TW)

(72) Inventor: **Wei-Ting Chao**, Taichung (TW)

(73) Assignee: **TUNGHAI UNIVERSITY**, Taichung (TW)

(**) Term: **15 Years**

(21) Appl. No.: **29/505,583**

(22) Filed: **Dec. 23, 2015**

(51) LOC (11) Cl. **24-02**

(52) U.S. Cl.

USPC **D24/225**

(58) **Field of Classification Search**

USPC D24/169, 216, 223-227, 230, 232-233; D10/81; 356/24; 422/64, 68.1, 72-73, 422/400-401, 404, 408, 412, 417, 422, 422/500, 502-506, 510, 552, 554, 559, 422/562; 204/403.01, 411, 450-453, 204/600-601; 435/283.1, 287.1, 287.2, 435/288.5, 288.7, 6.11, 289.1, 6.12, 29, 435/34, 4-5, 6.19, 7.1, 1.2, 173.7; 436/165-166, 180, 501, 518; 506/7, 9, 506/13, 18, 32, 33, 39, 40; 73/61.55, 73/61.71, 864.91

CLAIM

The ornamental design for a biochip, as shown and described.

DESCRIPTION

- FIG. 1 is a perspective view of a biochip;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.

1 Claim, 4 Drawing Sheets
